LOTTING MACHINE

Guy A. Staub, New Oxford, Pa.

Application June 21, 1951; Serial No. 232,781

5 Claims. (Cl. 273—144)

1

This invention relates to a lotting machine for mixing and discharging lotting balls one at a time and is particularly intended for playing a lotting game commercially known as "Bingo."

A further object of this invention is to provide a lotting machine which will thoroughly mix a number of lotting balls and discharge them one at a time, preferably one ball for each revolution of the machine.

A further object of this invention is to provide a lotting machine having a cylindrical mixing drum into which the entire supply of lotting balls may be placed and mixed by the rotation of the drum and which will discharge one ball at each rotation of the drum into a receiving tray from which the discharged ball may be manually removed and placed in a display rack having a special station having corresponding lot indicia for each lotting ball.

A further object of this invention is to provide a lotting machine having a lotting ball display rack provided with a ball chute at one end thereof to cooperate with a ball receiving trough in the lotting machine so that by picking up and tilting the display rack, all the balls thereon will roll to the ball chute at the end thereof and thence may be quickly discharged through the ball trough back into the drum of the lotting machine for the next play of the game.

Still a further object of this invention is to provide a lotting machine including a rotary lotting ball mixing drum mounted on a base board and a ball display rack of a size to compactly receive the base board of the lotting machine for storage purposes.

Still a further object of this invention is to provide a lotting machine including a horizontally mounted rotary drum having means to receive a plurality of balls at one end thereof and to discharge such balls at the other end thereof one at a time.

Still a further object of this invention is to provide a weighted lotting ball for use in a lotting machine wherein each ball has lotting indicia thereon and a weight so located in the ball with relation to the lotting indicia that the ball will normally rest on a position with the lotting indicia readily visible thereon.

With the foregoing and other objects in view, this invention comprises the combination, construction and arrangement of parts hereinafter set forth, claimed and disclosed in the accompanying drawings, wherein:

Fig. 1 is a top plan view of the lotting machine and ball display rack in playing position;

2

Fig. 2 is a longitudinal sectional view through the horizontally mounted drum.

Fig. 3 is a plan view of the flanged drum end plate.

Fig. 4 is a similar plan view of the ball receiving drum end plate.

Fig. 5 is a sectional view on line 5—5 of Fig. 2.

Fig. 6 is a sectional view on line 6—6 of Fig. 2, and

Fig. 7 is a plan view of a ball.

There is shown at 10 the lotting machine of this invention consisting of a base board 11 on which are mounted a pair of spaced apart brackets 12 to which are secured a pair of spaced apart drum end plates 13 and 14 for suitably closing the ends of the horizontally mounted cylindrical drum 15 therebetween.

The end plate 13 is provided with an inturned flange 16 extending inwardly a distance at least half a ball diameter, but preferably approximately equal to about a diameter of the lotting ball 17, this flange 16 extending about the top and sides of the plate 13. At the bottom, the plate 13 is free of the flange 16 a distance equal to several diameters of the ball 17 as at 18. A central opening 20 extends through a journal bearing 21 on the flange side of end plate 13, the journal bearing 21 extending inwardly somewhat greater than the distance of the inturned flange 16.

The other end plate 14 is provided with a large opening 22 therein greater than several diameters of the ball 17 and located adjacent its top. A trough 23 extends about the bottom and opposite sides of the opening 22 and serves as a ball entrance guide for feeding balls through the opening 22 into the drum 15. This plate 14 is also provided with an opening 24 at its center and an inwardly extending journal bearing 25 thereabout.

The drum 15 is horizontally mounted for rotation by means of spoked spiders 26 and 27 through which an axle shaft 28 extends into and through the journal bearings 20 and 25.

The spoked spider 26 includes four spokes 30 each secured near the entrance end of the drum 15 by means of feet 31 and provided with a central internally threaded hub 32 which is offset from the receiving end of drum 15 a distance equal to at least a diameter of the lotting ball 17 so as not to interfere with the entrance of the balls from trough 23 through opening 22 into the inside of the drum 15. A locking nut 34 cooperating with the end of thread 33 holds the axle 28 in fixed relation to the threaded

hub 32. The end of axle 28 is reduced as at 35 to fit into the journal opening 24 and a shoulder 36 between the reduced end 35 and threaded portion 33 abuts against a spacing washer 37 bearing against the end of journal bearing 25.

The other spoke spider 27 is secured by its feet 38 to the drum 15 at a distance from the discharge end of drum 15 somewhat greater than the width of the inturned flange 16. A sector member 40 extends between two adjacent spider spokes 41, and between the sector member 40 and the end of drum 15 there is provided a ball discharge opening 42. The axle shaft 28 extends to the center hub 43 of the spider 27 and then through the journal bearing 20 of end plate 13 and is then bent at right angles to provide a manually operable crank handle 44, should it be desired to manually operate the machine, particularly for use in a location where there is no electricity available for rotating the drum 15 through the small electric motor 45 having a plurality of different sized pulleys 46 for co-operation with a spring belt 47 about the outside of drum 15. The different sized pulleys 46 make it possible to vary the speed of rotation by shifting the spring belt 47 to the appropriate size pulley. If desired an additional set of pulleys can be provided for a greater speed reduction if necessary. A baffle disk 48 is secured at 50 within the drum 15 centrally on the axle shaft 28 to cause the balls to flow therearound as they pass from the entrance through the discharge end of drum 15 to more thoroughly mix the balls. As the drum 15 rotates, the discharge opening 42 passes around the inturned flange 16 and no ball can pass therethrough except when this discharge opening 42 is passing between the bottom ends of the flange 16 in the free area 18. A ball discharge chute is secured on the same bracket 12 on which the end plate 13 is secured. This ball discharge chute 51 has a length substantially equal to the distance between the ends 56 and 57 of the inturned end plate flange 16, and is inclined from the ball receiving end 52 toward the ball discharge end 53 and leads to a ball receiving tray 54 suitably located on the base board 11. The ball receiving end 52 is spaced from the adjacent end 56 of flange 16 a distance less than the diameter of a ball 17 while the discharge end 53 of chute 51 is spaced from the other end 57 of flange 16 a distance greater than the diameter of a ball 17 but less than one and one half diameters of the ball 17. Hence, as the drum 15 rotates in the direction of arrow 49, a ball may drop through the drum discharge opening 42 as this opening 42 passes out from under flange end 56 and travels along chute 51 as the opening approaches flange end 57. Due to the fact that the end 53 is not more than one and one half diameters away from the flange end 56, a second ball cannot fall therethrough but instead will remain in the drum 15 while the opening 42 passes under the flange end 57 to its next rotation.

To make the machine less noisy, the inside of the drum is provided with a lining of sound absorbing rubber 59 and segments of similar sound absorbing material are provided at 58 and 60 on the bottom of the inside of the end plates 13 and 14.

Each ball 17 is provided with lotting indicia 61 on one side thereof and a small weight 62 on the opposite side so that when the ball 17 is discharged into the ball receiving tray 54 it will come to rest with the lotting indicia 61 in readily

visible position. Then the ball is removed from the tray 54 and placed in the ball display rack 63 conveniently positioned adjacent the base board 11. The ball display rack 63 includes a master board 64 having a separate suitably identified station 65 for each lotting ball 17, there being approximately seventy-five stations 65 in the game commercially known as "Bingo" so that each ball 17 may be placed in its properly identified station 65 for verification when the player wins a game. The board 64 is provided with upwardly extending sides 66 somewhat higher than the diameter of a ball 17 and having one wall 67 spaced from the end of the board 64. This wall 67 is connected to the board 64 by a somewhat lower floor 68 and leads to an opening 70 at one end of floor 68. When a game is finished, the display rack 64 is picked up and its opening 70 is placed over the trough 23 and the rack suitably tilted to thereby cause all the balls to roll down into and on the floor 68 and through trough 23 and back into the drum 15.

In operation, the 75 lotting balls for the game "Bingo" are all placed through the trough 23 and opening 22 into the drum 15 and the drum is slowly rotated either by motor 45 or hand crank 44. One ball 17 is discharged with every rotation of the drum 15 and this rotation is slow enough for the discharge ball 17 to be picked up, its indicia read and announced, and the ball placed in its appropriate station 65 on the display rack 64. This is continued until the game is won, the result verified, and the balls returned to the drum 15 for another game.

While the device has been shown and the structure described in detail, it is obvious that this invention is not to be considered as being limited to the exact form disclosed, and that changes in detail and construction may be made therein within the scope of what is claimed, without departing from the spirit of this invention.

Having thus set forth and disclosed the nature of this invention, what is claimed is:

1. A lotting machine for mixing and dispensing lotting balls successively comprising a horizontally mounted open ended cylindrical drum, means for mounting said cylindrical drum for rotation about its horizontal axis comprising a pair of spaced apart mounted drum end plates, 45 one end plate having an inturned cylindrical flange extending inwardly of the drum at least half the width of the diameter of a ball across the top and opposite sides thereof, the bottom of said one end plate being free of such flange, 50 the other end plate having an opening therethrough adjacent its top of dimensions greater than the diameter of said balls, a ball entrance guide trough affixed to the outside of said other end plate about said opening therethrough, each 55 end plate having an aligned opening extending centrally therethrough, an axle shaft in said openings, a pair of drum carrying spoked spiders secured in said drum adjacent opposite ends, 60 said spiders having axle receiving openings therethrough at their centers, the spider spokes at the ball entrance guide trough end plate being offset at least the distance of a ball diameter from the drum end, the other spider being spaced from its drum end at least the width of the 65 inturned end plate flange, and of a full ball diameter, said drum having a ball discharge means 70 between said other spider and its end, comprising a ball discharge opening in said drum, an inclined ball discharge chute having a length substantially equal to the distance between the

bottom ends of said inturned end plate flange, the receiving end of said discharge chute being spaced from the adjacent end of said flange by less than the diameter of a lotting ball, the discharge end of said chute being spaced from the other end of said flange by more than one diameter and less than one and one half diameters of a lotting ball, whereby only one ball may discharge for each revolution of said drum.

2. A lotting machine for mixing and dispensing lotting balls one at a time comprising a horizontally mounted open ended cylindrical drum, means for mounting said cylindrical drum for rotation about its horizontal axis, a pair of spaced apart drum end plates, one end plate having an inturned cylindrical flange extending inwardly of the drum at least half the width of the diameter of a ball across the top and opposite sides thereof, the bottom of said one end plate being free of such flange, the other end plate having an opening therethrough adjacent its top of dimensions greater than the diameter of said balls, a ball entrance guide trough affixed to the outside of said other end plate about said opening therethrough, each end plate having an aligned journal opening extending centrally therethrough, an axle shaft journaled through said journal openings, a pair of drum carrying spoked spiders secured in said drum adjacent opposite ends, said spiders having axle receiving openings therethrough at their centers, the spider spokes at the ball entrance guide trough end plate being offset at least the distance of a ball diameter from the drum end, a baffle partition supported centrally of said axle shaft, the other spider being spaced from its drum end at least the width of the inturned end plate flange and of a full ball diameter, said drum having a ball discharge means between said other spider and its end, comprising a ball discharge opening in said drum, an inclined ball discharge chute having a length substantially equal to the distance between the bottom ends of said inturned end plate flange, the receiving end of said discharge chute being spaced from the adjacent end of said flange by less than the diameter of a lotting ball, the discharge end of said chute being spaced from the other end of said flange by more than one diameter and less than one and one half diameters of a lotting ball, whereby only one ball may discharge for each revolution of said drum.

3. A lotting machine for mixing and dispensing lotting balls one at a time comprising a horizontally mounted open ended cylindrical drum, means for mounting said cylindrical drum for rotation about its horizontal axis comprising a pair of spaced apart brackets, a drum end plate secured on each bracket, one end plate having an inturned cylindrical flange extending inwardly of the drum at least half the width of the diameter of a ball across the top and opposite sides thereof, the bottom of said one end plate being free of such flange, the other end plate having an opening therethrough adjacent its top of dimensions greater than several diameters of said balls, a multiple ball entrance guide trough affixed to the outside of said other end plate about said opening therethrough, each end plate having an aligned journal opening extending centrally therethrough, an axle shaft journaled through said journal openings, a thread on said axle shaft adjacent one end, a pair of drum carrying four spoked spiders secured in said drum adjacent opposite ends, said spiders having axle receiving

openings therethrough at their centers, one spider axle opening being threaded to cooperate with said axle threads, the spider spokes at the ball entrance guide trough end plate being offset at least the distance of a ball diameter from the drum end, the other spider being spaced from its drum end at least the width of the inturned end plate flange and of a full ball diameter, a sector member connecting two adjacent spokes of said other spider, said drum having a ball discharge means at said sector member between said other spider and its end, comprising a ball discharge opening in said drum, an inclined ball discharge chute having a length substantially equal to the distance between the bottom ends of said inturned end plate flange, the receiving end of said discharge chute being spaced from the adjacent end of said flange by less than the diameter of a lotting ball, the discharge end of said chute being spaced from the other end of said flange by more than one diameter and less than one and one half diameters of a lotting ball, whereby only one ball may discharge for each revolution of said drum.

4. A lotting machine for mixing and dispensing lotting balls one at a time comprising a horizontally mounted open ended cylindrical drum, means for mounting said cylindrical drum for rotation about its horizontal axis comprising a base board, a pair of spaced apart brackets mounted on said base board, a drum end plate secured on each bracket, one end plate having an inturned cylindrical flange extending inwardly of the drum at least half the width of the diameter of a ball across the top and opposite sides thereof, the bottom of said one end plate being free of such flange, the other end plate having an opening therethrough adjacent its top of dimensions greater than several diameters of said balls, a multiple ball entrance guide trough affixed to the outside of said other end plate about said opening therethrough, each end plate having an aligned journal opening extending centrally therethrough, an axle shaft journaled through said journal openings, the journal opening in one end plate being larger than the journal opening in the other end plate, said axle shaft having a reduced end to cooperate with the smaller journal opening, a shoulder on said axle shaft at the end of said reduced end limiting the axial movement of said shaft into said journal opening, a thread on said axle shaft adjacent said shoulder, a pair of drum carrying four spoked spiders secured in said drum adjacent opposite ends, said spiders having axle receiving openings therethrough, at their centers, one spider axle opening being threaded to cooperate with said axle threads, the spider spokes at the ball entrance guide trough end plate being offset at least the distance of a ball diameter from the drum end, the other spider being spaced from its drum end at least the width of the inturned end plate flange and of a full ball diameter, a sector member connecting two adjacent spokes of said other spider, said drum having a ball discharge opening means at said sector member between said other spider and its end, comprising a ball discharge opening in said drum, an inclined ball discharge chute having a length substantially equal to the distance between the bottom ends of said inturned end plate flange, the receiving end of said discharge chute being spaced from the adjacent end of said flange by less than the diameter of a lotting ball, the discharge end of said chute being spaced from the other end of said flange by more

than one diameter and less than one and one half diameters of a lotting ball, whereby only one ball may discharge for each revolution of said drum.

5. A lotting machine for mixing and dispensing lotting balls one at a time comprising a horizontally mounted open ended cylindrical drum, means for mounting said cylindrical drum for rotation about its horizontal axis comprising a base board, a pair of spaced apart brackets mounted on said base board, a drum end plate secured on each bracket, one end plate having an inturned cylindrical flange extending inwardly of the drum the width of the diameter of a ball across the top and opposite sides thereof, the bottom of said one end plate being free of such flange, the other end plate having an opening therethrough adjacent its top of dimensions greater than several diameters of said balls, a multiple ball entrance guide trough affixed to the outside of said other end plate about said opening therethrough, each end plate having an aligned journal opening extending centrally therethrough, an axle shaft journaled through said journal openings, the journal opening in one end plate being larger than the journal opening in the other end plate, said axle shaft having a reduced end to cooperate with the smaller journal opening, a shoulder on said axle shaft at the end of said reduced end limiting the axial movement of said shaft into said journal opening, a thread on said axle shaft adjacent said shoulder, a pair of drum carrying four spoked spiders secured in said drum adjacent opposite ends, said spiders having axle receiving openings therethrough at

their centers, one spider axle opening being threaded to cooperate with said axle threads, the spider spokes at the ball entrance guide trough end plate being offset at least the distance of a ball diameter from the drum end, a baffle partition supported centrally of said axle shaft, the large end of said axle shaft extending beyond its journal opening and bent into a crank handle, the other spider being spaced from its drum end at least the width of the inturned end plate flange, a sector member connecting two adjacent spokes of said other spider, said drum having a ball discharge opening means at said sector member between said other spider and its end, comprising a ball discharge opening in said drum, an inclined ball discharge chute having a length substantially equal to the distance between the bottom ends of said inturned end plate flange, the receiving end of said discharge chute being spaced from the adjacent end of said flange by less than the diameter of a lotting ball, the discharge end of said chute being spaced from the other end of said flange by more than one diameter and less than one and one half diameters of a lotting ball, whereby only one ball may discharge for each revolution of said drum.
